UNITED STATES PATENT OFFICE.

THOMAS KONDRA'S AND JOZEF KONDRA'S, OF IRON RIVER, MICHIGAN.

PLOW.

1,158,936.

Specification of Letters Patent.

Patented Nov. 2, 1915.

Application filed November 11, 1914. Serial No. 871,595.

To all whom it may concern:

Be it known that we, (1) THOMAS KONDRA'S and (2) JOZEF KONDRA'S, (1) a citizen of the United States and (2) subject of the Emperor of Russia, residing at 5 Iron River, in the county of Iron and State of Michigan, have invented certain new and useful Improvements in Plows, of which the following is a specification.

This invention relates to certain new and 10 useful improvements in plows.

The primary object of this invention is to 15 provide a plow having an adjustable draft appliance shiftable by the operator from a point adjacent the operating handles of the plow.

A further object is the provision of a 20 draft rod of a plow provided with vertical adjusting means operable from a point near the handles of the plow while the said rod is also laterally shiftable and adapted to be secured in position by a locking pin or bolt.

A still further object is to provide a 25 flexible draft appliance for a plow adapted for attaching a wiffle-tree or other connector of the motive power thereto, the same being provided with both vertical and laterally adjusting means for changing the connecting end of the draft appliance at will.

With these general objects in view and others that will appear as the nature of the 30 invention is better understood, the same consists in the novel combination and arrangement of parts to be hereinafter more 35 fully described, illustrated in the accompanying drawings and set forth in the appended claim.

In the drawings forming a part of this 40 application and in which like-designating characters refer to corresponding parts throughout the several views, Figure 1 is a perspective view of a plow provided with the device. Fig. 2 is a side elevation of the 45 forward portion of the plow. Fig. 3 is a top elevation thereof, and Fig. 4 is a transverse vertical sectional view taken through the front end of the plow.

Referring more in detail to the drawings, 50 the plow 10 illustrated is of substantially the usual form and is provided with a forwardly projecting beam 11, and rearwardly projecting handles 12 which have a connecting brace rod 13. A forward end of the 55 beam 11 has a draft rod 14 in the form of a mashed link connected thereto by means of a

clevis 14' and a short link 15, while a wiffle-tree hook 16 is swingingly attached to the forward end of the draft rod. A bracket 17 is adjustably mounted at the forward end of the plow beam 11 by means of a rod 18 secured to the bracket and slidably mounted within a sleeve 19 attached to the forward end of the beam and thus positioning the rod 18 transversely of the beam and at the forward end thereof. The sleeve 19 has a vertical opening therethrough adapted for the reception of a pin or locking bolt 20 which also projects through the desired one of the openings 21 vertically positioned through the said rod 18.

The bracket 17 has a rod 22 vertically 60 slideable therethrough which rod is provided with perforations 23 adapted to receive 65 teeth 24 of a wheel member 25 which is secured to a rod 26 being journaled in the bracket 17. The rear end of the rod 26 is journaled through a plate 27 centrally mounted upon the brace rod 13, while a 70 wheel 28 is attached to the rear free end of the rod 26 and is adjacently positioned to the plow handles 12 whereby the rod 26 may be revolved and by means of the engagement of the wheel 25 with the rod 22, 75 the said rod is vertically moved as may be 80 found desirable. An eye 29 is secured to the lower end of the rod 23 and the draft rod 14 freely projects therethrough.

From this detailed description of the 85 device, the complete operation thereof will be 90 at once apparent. The wiffle-tree hook of the draft rod is vertically adjustable whenever desired by means of the turn wheel 28 positioned near the plow handles so that 95 during the operation of plowing the wiffle tree connection may be lowered or raised at will for more perfectly placing the draft power in its best operative position. When desired also to change the side draft of the 100 motor plow, the rod 18 of the carrying bracket 17 is readily shiftable in the manner heretofore set forth.

While the forms of the invention herein 105 shown and described are what are believed to be the preferred embodiments thereof, it is nevertheless to be understood that minor changes may be made without departing from the spirit and scope of the invention as set forth in the claim.

What we claim as new is:—

In a plow, a beam, a substantially U-

shaped member secured detachably to the forward end of said beam, said member having a pair of rearwardly directed ears, a member slideable through said ears and having positive stop connection with the first member, a substantially vertical sleeve carried by the second member and having bearings formed therein, a shaft extending rearwardly through said bearings and 10 provided with an operating wheel at its rearward end, a spur gear provided with pin teeth fixed on said shaft between said bearings, a rod slideable through the second member in a substantially vertical direction 15 and provided with spaced openings to receive said pin teeth and engaged by said

teeth, a loop on the lower end of said rod, a link slideable and rotatable in said loop, a clevis carried by the forward end of said link, a U-shaped link pivoted to said beam and a third link connecting the U-shaped link and the first-mentioned link and having its ends twisted at right-angles to each other.

In testimony whereof we affix our signatures in presence of two witnesses.

THOMAS KONDRAS.
JOZEF KONDRAS.
